US00D902926S

(12) **United States Design Patent** (10) **Patent No.:** **US D902,926 S**
Andersson et al. (45) **Date of Patent:** **** Nov. 24, 2020**

(54) **TOUCH SCREEN**

(71) Applicant: **Siemens Aktiengesellschaft**, Munich (DE)

(72) Inventors: **Jan Andersson**, Erlangen (DE); **Nina Wendt**, Erlangen (DE)

(73) Assignee: **SIEMENS AKTIENGESELLSCHAFT**, Munich (DE)

(**) Term: **15 Years**

(21) Appl. No.: **29/648,694**

(22) Filed: **May 23, 2018**

(30) **Foreign Application Priority Data**

Nov. 24, 2017 (EM) 004520989

(51) **LOC (12) Cl.** **14-02**

(52) **U.S. Cl.**

USPC **D14/371**

(58) **Field of Classification Search**

USPC D14/300-302, 305, 307, 314, 336-337, D14/371, 374-384, 388-389, 448, D14/450-451, 210, 214, 126, 432, D14/444-446, 316-317, 323-324; 40/406, 427; D24/137-138, 160, 186; D20/39, 41-42; D6/300, 308, 310; D10/15, 21, 24, 50; D21/324-325, 329, D21/370; 361/521; 174/382, 552; D13/184, 162; D19/88, 113; D12/42

CPC E04H 1/1272; E04H 1/1222; G09F 13/00; G09F 9/00; G09F 9/3023; G09F 9/3026

(57) **CLAIM**

The ornamental design for a touch screen, as shown and described.

DESCRIPTION

FIG. 1 is a front view of a touch screen, showing our new design;

FIG. 2 is a rear view thereof;

FIG. 3 is a top view thereof;

FIG. 4 is a bottom view thereof;

FIG. 5 is a right side view thereof;

FIG. 6 is a left side view thereof; and,

FIG. 7 is a top, front and right side perspective view thereof.

The broken line portion of the figure drawings represents

structures forming no part of the claimed design.

1 Claim, 7 Drawing Sheets
